FRUIT BOX OR THE LIKE

Robert E. Rutledge, Kalamazoo, Mich., assignor
to Sutherland Paper Company, Kalamazoo,
Mich.

Application September 6, 1932. Serial No. 631,803

4 Claims. (Cl. 229—23)

The main objects of this invention are:

First, to provide a box for fruit or the like which may be made of comparatively light material and at the same time is strong and capable of supporting relatively heavy contents such as berries.

Second, to provide a box for fruit or the like which can be shipped in the knock-down and is very quickly set up, the bottom being effectively retained so that it is not likely to be dislocated in handling.

Objects relating to details and economies of my invention will appear from the description to follow. The invention is defined and pointed out in the claims.

15 A structure which is a preferred embodiment of my invention is illustrated in the accompanying drawings, in which:

Fig. 1 is a perspective view of a berry box embodying my invention.

20 Fig. 2 is an enlarged vertical fragmentary section on line 2—2 of Fig. 1.

Fig. 3 is an enlarged detail horizontal section on line 3—3 of Fig. 1.

Fig. 4 is a plan view of the blank from which the 25 outer wall member is formed.

Fig. 5 is a perspective view of the outer wall member set up.

Fig. 6 is a plan view of the inner member extended or in the flat.

30 Fig. 7 is a perspective view of a slightly modified form or embodiment of my invention.

Fig. 8 is an enlarged horizontal section on line 8—8 of Fig. 7.

Fig. 9 is a plan view of the inner member in the 35 flat.

My improved box comprises an outer band-like wall member 1 rectangular in horizontal section and downwardly tapered. This is formed of a blank 2 (see Fig. 4) scored at 3 to facilitate folding, the ends of the blank having overlapping portions 4 which are glued together.

At each corner, the outer wall member is provided with a slot 5, this slot being of considerable length and being formed by an elongated U-shaped slit indicated at 6 so that when the outer member is set up, as shown in Fig. 5, the slots 5 result and the parts cut out to form the slots projecting in tongues 7.

50 The inner member comprises a bottom 8 having integral side walls 9 on its edges, the bottom being of such dimensions as to fit within the outer member at or adjacent the bottom thereof as shown in Fig. 2. The inner side walls 9 are downwardly tapered so that they fit within the outer

walls constituting supporting and bracing members therefor.

Each side wall 9 of the inner member is provided with a tongue 10 on one vertical edge and a slot 11 on the opposite edge, the slots being 60 adapted to register with the slots of the outer wall members, the tongues 10 being adapted to engage the slots 5 in the outer wall member and corresponding to the slots 5 in length so that they effectively retain the inner member within the 65 outer.

The tongues 7 constitute guards for the tongues 10 preventing the accidental disengagement of the tongues 10 when the box is being handled. The engagement of the edges of the side walls 70 of the inner member with the walls of the outer member and these tongues serve to limit the downward movement of the inner member so that the bottom is effectively sustained and is locked against upward displacement, such as might occur from pressure of the fingers on the bottom in grasping or handling the box. When set up, the box is locked against wracking or collapsing movement by the coacting relation of the inner and outer walls and the box may be made 75 of quite light material and at the same time is satisfactory for the purpose.

80 In the modification shown in Figs. 7, 8 and 9, the inner wall member consists of the bottom 12 having side walls 13, only a pair of the side walls, however, having tongues 14, and the adjacent edge of the adjacent side wall has a slot 15 permitting the tongues to engage the slots in the outer member. This form is quite satisfactory as the inner member is quite effectively locked 85 or retained within the outer.

85 The two-piece structure is very quickly assembled, it only being necessary to erect or adjust the outer member to the position shown in Fig. 5, lay the inner member thereon, and push down on the bottom portion thereof when the retaining tongues will snap into place. The locking tongues for the inner member are of considerable width so that they effectively snap into place and they are not likely to be broken or torn off even when the box is formed of light and cheap stock, economy being obviously a feature clearly to be desired on account of the use to which the box is especially designed.

90 I have shown ventilating openings 16 but it will be understood that these openings can be arranged as desired although the openings in the side walls of the inner and outer members should register in order to be most effective.

95 I have not attempted to illustrate or describe 110

certain adaptations and modifications which I contemplate as it is believed that this disclosure will enable those skilled in the art to embody or adapt my improvements as may be desired.

5 Having thus described my invention, what I claim as new and desire to secure by Letters Patent, is:

1. A box comprising a band-like downwardly tapered outer wall member having vertical slots 10 at the corners thereof, portions of the walls being partially severed to provide the slots and constituting projecting guard tongues, and an inner member comprising a bottom and downwardly tapered inner side walls on the edges thereof 15 fitting within the outer wall member, each of said inner side walls having a notch on one vertical edge aligning with said slots in said outer wall member and a tongue on the opposite vertical edge engaging the slots whereby the inner member is retained and supported within the outer, the said tongues on the outer member constituting guards for the retaining tongues on the inner.
2. A box comprising a band-like downwardly 25 tapered outer wall member having vertical slots at the corners thereof, and an inner member comprising a bottom and downwardly tapered inner side walls on the edges thereof fitting within the outer wall member, each of said inner 30 side walls having a notch on one vertical edge aligning with said slots in said outer wall mem-

ber and a tongue on the opposite vertical edge engaging and fitting the slots whereby the inner member is retained and supported within the outer.

3. A box comprising a band-like downwardly tapered outer wall member having vertical slots at the corners thereof, portions of the walls being partially severed to provide the slots and constituting projecting guard tongues, and an inner member comprising a bottom and downwardly tapered inner side walls on the edges thereof fitting within the outer wall member, certain of said inner side walls having a tongue on one vertical edge engaging and fitting the slots whereby the inner member is retained and supported within the outer, the said tongues on the outer member constituting guards for the retaining tongues on the inner.

4. A box comprising an outer downwardly tapered band-like outer wall member having a vertical slot at each corner thereof, and an inner member comprising a bottom and downwardly tapered inner side walls fitting within said outer wall member, certain of said inner side walls having tongues on their edges engaging and fitting said slots in the outer member, the adjacent edges of adjacent inner side walls having notches aligning with said slots and receiving and fitting said tongues.
